(57) **CLAIM**

The ornamental design for small low-profile tiltable mount for flat panel displays, as shown and described.

DESCRIPTION

FIG. 1 is a top, right isometric view of a small low-profile tiltable mount for flat panel displays showing our new design in a vertical configuration.

FIG. 2 is a front elevational view thereof.

FIG. 3 is a rear elevational view thereof.

FIG. 4 is a right-side elevational view thereof; the left-side view is a mirror image of FIG. 4.

FIG. 5 is a top plan view thereof.

FIG. 6 is a bottom plan view thereof; and,

FIG. 7 is a top, right isometric view thereof in a tilted configuration.
